S.R. Bryant
Anchor Tripper

N° 12,435. Patented Feb. 27, 1855.

UNITED STATES PATENT OFFICE.

SAMUEL R. BRYANT, OF NEW YORK, N. Y.

ANCHOR-TRIPPER.

Specification of Letters Patent No. 12,435, dated February 27, 1855.

To all whom it may concern:

Be it known that I, SAMUEL R. BRYANT, of New York, in the county of New York and State of New York, have invented a new and improved mode of constructing a machine for the suspension of and dropping of anchors of vessels or for any other purpose where it is required to have a bearing that is capable of supporting a desired weight any length of time or letting the same fall at will and instantaneously; and I do hereby declare that the following is a full, clear, and exact description of the construction and operation of the same, reference being had to the annexed drawings, making a part of this specification, in which—

Figure 1 is a perspective view and Fig. 2 a longitudinal section.

20 A, is a bed or iron frame made in a suitable shape and size to fit the cathead or other part where it is to be placed.

a, is a projection or guard cast on the front side at the top of bed frame A, and 25 for the purpose of preventing the chain link from sliding off of its supporter B.

b, is a hollow semicircular abutment cast on the top side of bed frame A, within which, the jointed end of the pawl, C, works, and for the purpose of sustaining 30 the pressure caused by the anchor or weight hanging on the supporter, B, the pressure being transmitted to it through the pawl, C, being in a line with and in contact with the 35 supporter, B, and the abutment, b,

B, is the support, (on which the link hangs with weight attached, to be made of brass or iron and of suitable figure) having its upper end, g, so curved, that when 40 the weight is hanging upon it, it shall press sufficiently against the pawl, C, so that on removing the pawl, C, the weight shall force the supporter, B, within the openings, e, e, and drop.

45 C, is a pawl lying on the top of the bed frame, A, to be moved laterally and is kept in its position by a pin, f, which is secured within the circle of the abutment, b, and on which pin, it works loosely; that the abutment, b, may receive whatever pressure the weight of the anchor, or other weight, suspended may produce.

D, is a holdfast, jointed on the top side of

the pawl, C, near the abutment end, b, and is to be lifted vertically, with an opening 55 made in its opposite end to fit the head of the supporter, B, it can be used, either alone or in combination with the pawl, C, or the pawl, C, alone as may be required.

c, is a step, cast on the inner side of bed 60 frame, A, for the holding and guiding of the supporter, B, or may be cast on the front side as required.

d, is a rib, or tooth, cast on the underside of the top of bed frame, A, for entering 65 the timber on which it is to be fastened, thereby adding to its greater security.

e, e, are openings in the top, and front sides of the bed frame, A, midway, for receiving the supporter, B, and allowing it to 70 be worked back and forth.

f, is a pin secured in the top side of bed frame A, for the holding in its place of the pawl, C, and holdfast, D.

Mode of operation: Having dropped the 75 small end of the supporter, B, into its step, c, and within the openings, e, e, and having secured the pawl, C, and holdfast, D, to the bed frame, A, it may be bolted to the cathead or other place where required; then 80 move the supporter, B, back until its curved corner comes flush with the front of frame, A, and shove the chain link up within the space between the guard, a, and frame, B, until it is sufficiently high to allow the 85 covered end, g, of the supporter, B, to be again moved to the front, and within the link; then move the pawl, C, until it arrives directly in the rear of the upper end of the supporter, B, and drop the holdfast, D, 90 when it will be locked, allow the weight to hang as all is secure. When it is required to drop the anchor or weight, lift the holdfast, D, and shove the pawl, C, to one side when it will drop instantly, and may be 95 replaced, and the dropping repeated as already described.

What I claim as my invention and desire to secure by Letters Patent is the following:

The supporter, B, the pawl, C, and the 100 holdfast, D, as arranged in relation to the guard, a, for the purposes herein set forth.

SAMUEL R. BRYANT.
